OIL BURNER

William F. Klockau, Moline, Ill.

Application August 2, 1939, Serial No. 287,873

12 Claims. (Cl. 158—78)

The present invention relates to oil burners, and has particular reference to the provision of improved means for thermally insulating the burner nozzle from heat radiated from the flame and the combustion chamber.

For a considerable time, manufacturers of boilers and furnaces have been endeavoring to develop successful heating units of relatively small size, i. e., in the neighborhood of 80,000 B. t. u. output, in which oil is used for fuel. The principal difficulty encountered in the development of these small heating units is that of obtaining a burner which can successfully burn oil at a rate low enough to overcome high stack losses. Heretofore, there have been very few burners, if any, capable of giving satisfactory performance when using nozzles of such small capacity as approximately one gallon per hour, and even these burners usually produce too much heat for many of the smaller heating units to absorb efficiently.

There is a considerable demand for small heating units of the approximate size above mentioned, owing to the large number of small four and five room homes being built at the present time. For example, an oil burner that can successfully burn oil at a rate as low as $\frac{3}{4}$ gallon per hour would fill an immediate need. It is well known, of course, that vaporizing burners and low pressure burners are now available in relatively small sizes. However, the vaporizing burners are unsatisfactory inasmuch as they require a light grade, high priced fuel and are difficult to operate automatically. The low pressure burners are too noisy in their operation, and are relatively expensive to manufacture. Contrasted to these, the high pressure burner is the most desirable or the only practical type of burner now known as having definite potentialities for this market. This type of burner is low in cost, quiet in operation, requires little service, and uses the heaviest grades of domestic fuel oil.

The principal difficulty experienced with pressure type oil burners using nozzles of very small capacity has been the clogging of the nozzles, owing to the extremely fine passages necessary to keep the fuel delivery rate low enough at atomizing pressures. For example, the slots in a typical one-gallon per hour nozzle are approximately .008 inch wide. Screens and filters that will screen out particles much smaller than .008 inch in diameter have been used in conjunction with these one-gallon per hour nozzles, but such nozzles are still subject to clogging, and must be cleaned at frequent intervals. Under all but the most extremely favorable conditions, these inter-

vals are so short that such nozzles have generally been deemed impractical, at least for ordinary operating conditions.

From the fact that the use of filters of smaller screening size than the size of the nozzle slots and orifice does not avoid this frequent clogging of the slots, it follows that this clogging is not due to sediment or particles suspended in the oil. I have determined by conclusive experiments that this frequent clogging of extremely small capacity nozzles is due to high temperatures, particularly the action of radiant heat from the combustion space impinging on the nozzle. Fuel oil is a compound of hydrocarbons of a complex nature, whose molecules are distilled off by heat. Some molecules pass off at relatively low temperatures, and as the temperature rises more and more pass off. Finally, a temperature is reached (in the neighborhood of 680° F.) where no more evaporation takes place, but a sticky tar-like substance remains. A very small deposit of this substance will interfere with the proper spraying action of the nozzle, or will clog it up entirely.

Moreover, it is not necessary for the nozzle to attain a temperature of 680° F. to cause it to clog. If only 40% or 50% of the oil remaining in the nozzle is distilled off, the remaining oil is of a consistency that will be very difficult to expel when the burner again resumes operation. Gradually, a mass of material accumulates in the nozzle until clogging occurs. It must be borne in mind that only a very minute quantity of oil remains in the nozzle passages after a burner stops operating, and that distillation takes place very rapidly. Furthermore, at temperatures as low as 200° F. the liquid oil will be driven off, while solids and semi-fluid residues will remain in the nozzle passages. A small quantity of this material is deposited after each burner operation, until finally the nozzle clogs.

By placing a small thermocouple tightly against the nozzle tip, I have made accurate temperature measurements of the nozzle during burner operations and immediately following cessation of burner operation. These tests show that the nozzle begins to heat up very rapidly after the burner is started, notwithstanding the fact that cold air is being passed over the burner at a relatively high velocity, and cold oil is being passed through it. The temperature rise is due to the absorption of radiant heat from the flame and adjacent refractory and metallic parts. Numerous tests were made on various types of boilers and furnaces, as well as with different designs of combustion chambers and combustion

chamber material, during which the rate of temperature rise, and the maximum temperature reached, varied under different conditions. The lowest maximum temperature recorded while the burner was in operation was 260° F., while the highest was 490° F. Maximum temperature was attained in from ten to fifteen minutes of operation from a cold start, depending upon conditions. Immediately after stopping the burner, the temperature usually rises about ten degrees F. and then slowly drops. After thirty minutes or so it comes down to about 150° F.

The foregoing observations and experiments have demonstrated to me the importance of shielding the nozzle tip from the radiant heat of the flame while the burner is in operation, and also of shielding the nozzle tip from the radiant heat of the combustion chamber after the burner has stopped. To the attainment of these ends, I have devised different forms of improved heat shields for the burner nozzle, which I shall now describe in connection with the accompanying drawings. In these drawings:

Figure 1 is an axial sectional view through a conventional design of burner of the type described above, illustrating one embodiment of my improved heat shield;

Figure 2 is a perspective view of this heat shield;

Figure 3 is a fragmentary view similar to Figure 1, showing another embodiment of my improved heat shield;

Figures 4 and 5 are front elevational and sectional views, respectively, on a larger scale, of the nozzle shield illustrated in Figure 3;

Figure 6 is an axial sectional view through a conventional burner, illustrating my invention embodied in the form of a combination nozzle shield and electrode bracket;

Figure 7 is a transverse sectional view taken approximately on the plane of the line 7—7 of Figure 6, and

Figure 8 is a fragmentary sectional view similar to Figure 6 but showing the use of a different form of nozzle shield, similar to that illustrated in Figure 3.

One of the refractory enclosing walls of the combustion chamber is indicated at 12. Entering the combustion chamber through this wall is the abovedescribed type of burner assembly comprising a draft tube 14 for the air supply, and an oil pipe 16 for the fuel supply. The inner end of the draft tube 14 is usually provided with an air deflector ring 15 which is fastened to or formed integral with the draft tube. This deflector ring serves to constrict the air stream to a high velocity tapering jet converging toward a point beyond the nozzle head. As hereinafter described in connection with Figure 3, this deflector ring may be provided with inclined vanes for imparting a helical or spiral twist to the air stream. Secured to the inner end of the oil pipe 16 is the nozzle body 17. The nozzle tip 18 at the inner end of this body is provided with a relatively small central orifice 19. The slots or passageways which determine the capacity of the burner are usually located in the body of the nozzle, anterior to this discharge orifice 19. The draft tube 14 is usually connected to receive air under pressure from a displacement blower, turbo blower, fan or the like. The oil pipe 16 is usually connected to receive fuel oil under pressure from a gear pump, pressure chamber, or other source of pressure feed. Ignition is usually effected electrically in these burners by a spark drawn

between two electrodes 22 disposed slightly beyond and above the nozzle tip 18. These electrodes are mounted in sleeves 23 of porcelain or other suitable insulating material which are clamped in the arms of a supporting spider 24. The spider clamps about the oil pipe 16, and comprises three equidistantly spaced arms 24a—24a and 24b which extend radially outwardly into proximity to the inner surface of the draft tube 14, thereby centering the oil pipe within the draft tube. The two spider arms 24a—24a are of split clamping construction adapted to clamp over the insulating sleeves 23 of the electrodes.

The embodiment of heat shield illustrated in Figures 1 and 2 is of a readily attachable and detachable design adapted for widespread use on various constructions of burners now on the market, without necessitating any change in the burner construction. In this embodiment, the shield, designated 27 in its entirety, is in the form of a semi-spherical or dome-shaped member 28 having an arm 29 extending rearwardly from the edge of the member 28, which arm is formed with a U-shaped clamp 30 at its inner end. An aperture 31 located centrally in the semi-spherical cap portion 28 is adapted to align with the jet orifice 19 in the nozzle tip. The entire unit can be readily formed as a sheet metal stamping, or can be cast, as desired. I prefer to construct it as a stainless steel stamping, and to give a high polish to the outer surface of the spherical cap portion 28 for reflecting a maximum amount of the radiant heat impinging thereon. The shield is operatively positioned in the burner by merely snapping the U-shaped spring clamp portion 30 over the body 17 of the nozzle. The aperture 31 in the shield is aligned with the nozzle orifice 19 as above stated, and the diameter of said aperture 31 is preferably so proportioned that the entire conical discharge 32 from the nozzle orifice 19 just clears the edge of the shield aperture 31. The spherical portion of the shield is spaced axially from the nozzle tip 18 so as to leave an air space 33 between the shield and tip. A relatively rapid flow of air passes through this space 33 and out through the aperture 31 in the shield, this flow of air resulting from the forced draft through the draft tube 14, and also from the aspirating action of the fuel nozzle, the air flow exerting a cooling influence on the nozzle tip and also on the inner surface of the heat shield. It will be seen from the foregoing that my improved shield will thermally insulate the nozzle tip from radiant heat emanating from the flame during burner operation, and will also act as a thermal barrier against the radiant heat of the combustion chamber after the burner has ceased operating. During the running period, the high speed air flow impelled through the passageway 33 by the forced draft and by the aspirating action of the nozzle exerts a substantial cooling effect on the nozzle tip, shield 28, arm 29, clamp 30, etc., and during the non-running period an air flow is also impelled through this passageway 33 by reason of the natural draft through the combustion chamber. This air flow prevents convection heat from reaching the nozzle tip. If desired, the supporting arm portion 29 of the shield may be made somewhat longer, so that the spring clamp portion 30 can be engaged over the oil pipe 16 instead of over the nozzle head.

In Figures 3, 4 and 5, I have illustrated a modified construction of heat shield in which a

relatively large aggregate area of opening is effective in the outer portion of the shield for the circulation of a considerable amount of air therethrough, but through which increased area of opening radiant heat cannot pass from the flame or from the combustion chamber back to the nozzle tip. The construction is analogous to a Venetian blind or overlapping vane effect for permitting a large volume of air to flow through the shield, but without affording any straight line paths which would enable radiant heat to reach the nozzle tip. In the preferred construction of such embodiment, the shield comprises a short cylindrical member 36, preferably composed of tubing, and a plurality of vanes 37 mounted in staggered or offset relation across the front end of this cylindrical section. The latter end is formed with a series of notches 38 occurring around the entire tube and inclined in the relation of saw teeth. The vanes 37 are individual stampings of segmental form, having their narrow ends cylindrically notched or rounded out, as indicated at 39, so as to form the central aperture 31 of the shield when the vanes are all assembled over the end of the cylindrical section. This assembly of the vanes is preferably effected by welding the rounded outer edges of the vanes to the outer faces of the notches 38. The vanes are preferably of sufficient width so that the edges of adjacent vanes will overlap the requisite amount to prevent radiant heat from the flame or from the combustion space reaching the nozzle tip 18, this overlapping relation being indicated in dotted lines in Figure 4. The arm 29' and U-shaped spring clamp 30' extend from the front portion of the shield in substantially the same relation described of the arm 29 and clamp 30 in Figure 1, being either formed integral with the cylindrical section 36, or in the form of a separate stamping which is welded or riveted to said cylindrical section. This embodiment of heat shield is assembled over the nozzle in the same relation described above, and performs the similar function of preventing radiant heat from the flame or from the combustion space from reaching the nozzle tip. The relatively large aggregate area of the openings between the staggered vanes enables a large volume of air to be circulated through the shield. It will be noted that the inclined disposal of the vanes 37 results in a helical or spiral twist being imparted to the air flowing through the shield. In many instances, the air deflector ring 15 is provided with inclined deflecting vanes 15' for imparting a helical motion to the main body of air discharged through said deflector ring. These inclined vanes 15' may be employed in connection with either of the embodiments illustrated in Figure 1 or 3, and when employed in connection with the embodiment of Figure 3 the vanes 15' and 37 are preferably arranged to have the same direction of inclination, so that the helical motion imparted to the air will be in the same direction for both the deflector ring and the heat shield.

The embodiment illustrated in Figures 6 and 7 is in the form of a combination nozzle shield and electrode supporting bracket. It comprises a relatively long sleeve 42 provided with an end cap or end head 43, this unit enveloping the entire nozzle body 17 and also the outer portion of the oil pipe 16. A flaring skirt portion 44 at the opposite end of the sleeve 42 deflects an added amount of air from the draft tube 14

into the sleeve 42. Spider arms 45 extend inwardly from this skirt portion 44 to a central mounting boss 46 which slips over the oil pipe 16 and is rigidly secured thereto by the set screw 47. It will be noted that the entire forward portion of the sleeve 42 and the end cap 43 are spaced entirely out of contact with the nozzle 17 and nozzle supply pipe 16, and that the spider structure 45 is the only supporting means capable of conducting heat from the heat shield to the nozzle. This supporting structure is spaced so far to the rear of the nozzle head that the heat must travel a considerable distance along the shield to reach the spider structure, and this travel is in opposition to the cooling flow of air traveling in contact with the heat shield. The result is that very little heat reaches the spider structure. As best shown in Figure 7, electrode supporting arms 51-51 project outwardly from the sleeve 42, and are formed with bifurcated outer ends for effecting clamped engagement over the insulating sleeves 23 of the electrodes. Screws 52-52 pass through the bifurcated ends of these arms for clamping the latter over the electrode sleeves. A third arm 54 also extends from the heat shielding sleeve 42 for engaging with the inner surface of the draft pipe 14, whereby to center the sleeve 42 and burner nozzle within said draft pipe. The electrode supporting arms 51-51 and the third arm 54 function as heat dissipating surfaces for dissipating heat from the rear portion of the heat shield.

The heat shielding end head 43 may be formed integrally with the sleeve 42, or may be in the form of a separate sheet metal stamping, as illustrated. I preferably make it of stainless steel, and apply a high polish to the outer surface thereof, as previously described in connection with Figures 1 and 2. The inner edge of said end cap is formed with an inwardly crimped bead 56 adapted to snap into an annular groove 57 formed in the outer end of the sleeve 42. At one point around the sleeve there is formed a longitudinally deeper recess 58 for receiving the bit end of a screwdriver, by the rotation of which the cap 43 can be forced off the end of the sleeve 42. The aperture 61 in the removable head member 43 is preferably so proportioned that the entire conical discharge 32 from the nozzle orifice 19 just clears the edge of this aperture 61, as previously described in connection with Figure 1. Said end cap is spaced axially from the nozzle tip 18 so as to leave an air passageway 63 between the end cap or shield and the nozzle tip. The operation of this embodiment will be readily understood from the description of the preceding embodiments. A greater degree of thermal shielding is obtained by employing the sleeve 42 to envelop the entire nozzle and adjacent portion of the oil supply pipe.

The embodiment illustrated in Figure 8 employs the same construction and arrangement of thermally insulating sleeve 42, but in lieu of the end head 43 of Figure 6 it employs an end head or shield portion 65 which is substantially the same as that illustrated in Figures 3, 4 and 5. That is to say, it comprises a tubular portion 66, and a plurality of vanes 67 mounted in staggered or offset relation across the front end of this tubular section, in substantially the same relation as the tubular member 36 and vanes 37. The other edge of this tubular section is formed with an inwardly crimped bead 71 which is adapted to snap into the annular groove 57

formed in the outer end of the sleeve 42. In either of the two embodiments illustrated in Figures 6 and 8, the air deflector ring 15 may be provided with inclined deflecting vanes 15', and when employed in connection with the embodiment of Figure 8 the vanes 15' and 67 are preferably arranged to have the same direction of inclination. If desired, any one of the embodiments illustrated in Figures 1, 3, 6 and 8 may be arranged so that the heat shield has direct mounting attachment or support on this air deflecting ring 15.

While I have illustrated and described what I regard to be the preferred embodiments of my invention, nevertheless it will be understood that such are merely exemplary and that numerous modifications and rearrangements may be made therein without departing from the essence of the invention. In this regard, while my invention has its greatest field of utility in high pressure burners, nevertheless it also has advantageous utility in all nozzle types of burners.

I claim:

1. In a burner of the class described including a nozzle adapted to discharge liquid fuel under pressure into a combustion chamber, the combination of a thermally insulating shield surrounding said nozzle and operative to insulate said nozzle from the radiant heat of the flame during operation of the burner and from the radiant heat of the combustion chamber following cessation of operation of the burner, said shield having a substantially central aperture therein aligned with the nozzle orifice for the discharge of fuel into the combustion chamber, and having secondary apertures for the passage of air through said shield, said secondary apertures being angularly inclined in such relation as to prevent said radiant heat of the flame and of the combustion chamber passing through said latter apertures and impinging on said nozzle.

2. In a burner of the class described including a nozzle having an orifice adapted to discharge liquid fuel under pressure into a combustion chamber, the combination of a thermally insulating shield surrounding said nozzle and operative to insulate said nozzle from the radiant heat of the flame during operation of the burner and from the radiant heat of the combustion chamber following cessation of operation of the burner, said shield comprising a cylindrical body portion having its front end notched in saw-tooth profile, vane segments seated in said notches in overlapping relation to provide apertures through which air can pass but through which radiant heat cannot reach said nozzle, and an oil transmitting aperture in said shield aligned with the nozzle orifice for the discharge of fuel into the combustion chamber.

3. In a liquid fuel burner comprising an air duct adapted to discharge air into a combustion chamber and a nozzle within said air duct adapted to discharge liquid fuel under pressure into said combustion chamber, the combination of a heat shield surrounding said nozzle for shielding the latter from the radiant heat of the flame during operation of the burner and from the radiant heat of the combustion chamber following cessation of operation of the burner, said heat shield comprising a relatively long tubular casting surrounding said nozzle in spaced relation thereto to define an air passageway therearound, a sheet metal end head mounted on the front end of said tubular casting in position to substantially enclose and shield said nozzle from

the radiant heat emanating from either of said sources, said end head having an aperture therein through which the liquid fuel discharge from said nozzle occurs, a spider at the rear end of said tubular casting for maintaining said nozzle and tubular casting in radially spaced relation, said end head and the forward portion of said tubular casting being spaced entirely out of heat conducting contact with said nozzle to minimize the conduction of heat to the latter, said tubular casting having an annular groove around its outer end, and said end head having an annular bead formed around the inner end thereof for releasably engaging in said groove.

4. In a liquid fuel burner comprising an air duct adapted to discharge air into a combustion chamber and a nozzle within said air duct adapted to discharge liquid fuel under pressure into said combustion chamber, the combination of a heat shield surrounding said nozzle for shielding the latter from the radiant heat of the flame during operation of the burner and from the radiant heat of the combustion chamber following cessation of operation of the burner, said heat shield comprising a relatively long sleeve member surrounding said nozzle in spaced relation thereto to define an air passageway therearound, an end head member mounted on the front end of said sleeve member in position to substantially enclose and shield said nozzle from the radiant heat emanating from either of said sources, said end head member having an aperture therein through which the liquid fuel discharge from said nozzle occurs, a spider at the rear end of said sleeve for maintaining said nozzle and sleeve in radially spaced relation, said end head member and the forward portion of said sleeve being spaced out of heat conducting contact with said nozzle to minimize the conduction of heat to the latter, and means for releasably coupling said head member to said sleeve member, comprising an annular groove formed around the outer end of said sleeve member, and an annular bead formed around the inner end of said head member for releasably engaging in said groove.

5. In a liquid fuel burner comprising an air duct adapted to discharge air into a combustion chamber and a nozzle within said air duct adapted to discharge liquid fuel under pressure into said combustion chamber, the combination of a heat shield surrounding said nozzle for shielding the latter from the radiant heat of the flame during operation of the burner and from the radiant heat of the combustion chamber following cessation of operation of the burner, said heat shield comprising a relatively long sleeve surrounding said nozzle in spaced relation thereto to define an air passageway therearound, an end head mounted on the front end of said sleeve in position to substantially enclose and shield said nozzle from the radiant heat emanating from either of said sources, said end head having an aperture therein through which the liquid fuel discharge from said nozzle occurs, a spider at the rear end of said sleeve for maintaining said nozzle and sleeve in radially spaced relation, said end head and the forward portion of said sleeve being spaced out of heat conducting contact with said nozzle to minimize the conduction of heat to the latter, and releasable coupling means for coupling said end head to said sleeve.

6. In a liquid fuel burner comprising an air duct adapted to discharge air into a combustion

chamber, and a nozzle member comprising a nozzle supply pipe and a nozzle head adapted to discharge liquid fuel under pressure into said combustion chamber, the combination of a heat shield surrounding said nozzle member for shielding the latter from the radiant heat of the flame during operation of the burner, and from the radiant heat of the combustion chamber upon cessation of operation of the burner, said heat shield comprising a relatively long sleeve surrounding said nozzle member in spaced relation thereto to define an air passage therearound, and an end head mounted on the front end of said sleeve in position to substantially enclose and shield said nozzle member from the radiant heat emanating from either of said sources, a spider at the rear end of said sleeve for maintaining said nozzle member and sleeve in radially spaced relation, said end head and the forward portion of said sleeve being spaced out of heat conducting contact with said nozzle member to minimize the conduction of heat to the latter, said sleeve having an annular groove around its outer end, an annular bead formed around the inner end of said end head releasably engaging in said groove, said end head having its front portion notched in saw-tooth profile, and vane segments seated in said notches in overlapping relation to provide apertures through which air can pass but through which radiant heat cannot reach said nozzle member.

7. In a liquid fuel burner comprising an air duct adapted to discharge air into a combustion chamber, and a nozzle member comprising a nozzle supply pipe and a nozzle head adapted to discharge liquid fuel under pressure into said combustion chamber, the combination of a heat shield surrounding said nozzle member for shielding the latter from the radiant heat of the flame during operation of the burner, and from the radiant heat of the combustion chamber upon cessation of operation of the burner, said heat shield comprising a relatively long sleeve surrounding said nozzle member in spaced relation thereto to define an air passage therearound, and an end head mounted on the front end of said sleeve in position to substantially enclose and shield said nozzle member from the radiant heat emanating from either of said sources, a spider at the rear end of said sleeve for maintaining said nozzle member and sleeve in radially spaced relation, said end head and the forward portion of said sleeve being spaced out of heat conducting contact with said nozzle member to minimize the conduction of heat to the latter, said end head having its front portion notched in saw-tooth profile, and vane segments seated in said notches in overlapping relation to provide apertures through which air can pass but through which radiant heat cannot reach said nozzle member.

8. In a liquid fuel burner comprising an air duct adapted to discharge air into a combustion chamber, and a nozzle member comprising a nozzle supply pipe and a nozzle head adapted to discharge liquid fuel under pressure into said combustion chamber, the combination of a heat shield surrounding said nozzle member for shielding the latter from the radiant heat of the flame during operation of the burner, and from the radiant heat of the combustion chamber immediately after stopping the operation of the burner, said heat shield comprising a supporting casting attached to said nozzle supply pipe at a

- 5 point to the rear of said nozzle head, and a sheet metal end head mounted on said supporting casting in position to substantially enclose and shield said nozzle member from the radiant heat emanating from either of said sources, said supporting casting having an annular seating surface, said sheet metal end head having a cooperating annular seating surface for releasably engaging the seating surface on said casting, said heat shield being supported entirely out of contact with said nozzle supply pipe and nozzle head except at said point of attachment of said supporting casting on said nozzle supply pipe, whereby to minimize the conduction of heat from said
- 10 15 20 25 30 35 40 45 50 55 60 65 70
- heat shield to said nozzle head, the front of said end head being of substantially semi-spherical formation and having an aperture through which the liquid fuel discharge from said nozzle occurs, said aperture having a diameter less than half the diameter of said nozzle head whereby said end head shields the major frontal area of said nozzle head from radiant heat.
9. In a liquid fuel burner comprising a draft tube adapted to discharge air into a combustion chamber, and a nozzle member comprising a nozzle supply pipe and a nozzle head having an orifice adapted to discharge liquid fuel under pressure longitudinally of said draft tube into said combustion chamber, the combination of a heat shield surrounding said nozzle member within said draft tube for shielding the nozzle member from the radiant heat of the flame during operation of the burner, and from the radiant heat of the combustion chamber immediately following cessation of operation of the burner, the outer surfaces of said heat shield being cooled by the outer stream of air flowing through said draft tube, said heat shield comprising a supporting casting surrounding said nozzle member, and a sheet metal end head mounted on said supporting casting in position to substantially enclose and shield said nozzle member from the radiant heat emanating from either of said sources, said end head being supported in spaced relation to said nozzle member to permit air flow therebetween, means for detachably connecting said end head to said supporting casting the front of said end head having a relatively small aperture through which the liquid fuel discharge from said nozzle occurs, said aperture having a diameter less than half the diameter of said nozzle head whereby said end head shields the major frontal area of said nozzle head from said radiant heat.
10. In a liquid fuel burner comprising a draft tube adapted to discharge air into a combustion chamber, and a nozzle member comprising a nozzle supply pipe and a nozzle head having an orifice adapted to discharge liquid fuel under pressure longitudinally of said draft tube into said combustion chamber, said nozzle head being of relatively small size and comprising an outer portion inclined inwardly toward said nozzle orifice the combination of a heat shield surrounding said nozzle head for shielding the latter from the radiant heat of the flame during operation of the burner, and from the radiant heat of the combustion chamber immediately following cessation of operation of the burner, said heat shield comprising a heat reflecting shell enveloping said nozzle head in spaced relation thereto to define a passage for a cooling flow of air therebetween, and mounting means associated with the rear portion of said reflecting

shell for supporting the latter in such relation as to conduct a minimum amount of heat from said reflecting shell to said nozzle member, said reflecting shell extending across the front surface of said nozzle head and having a relatively restricted aperture therein through which the liquid fuel is discharged from said nozzle head and through which said cooling flow of air is discharged, the outer portion of said reflecting shell extending inwardly at a more acute angle than the outer portion of said nozzle head so as to dispose the plane of said aperture in close proximity to the plane of the nozzle orifice, and the diameter of said aperture being much less than the diameter of said nozzle head, whereby said passage for conducting cooling air diminishes in effective area adjacent to said aperture to accelerate the flow of air through said aperture, and whereby said reflecting shell shields the major frontal area of said nozzle head from the radiant heat of the flame and of the combustion chamber.

11. In a liquid fuel burner comprising an air duct adapted to discharge air into a combustion chamber, and a nozzle member comprising a nozzle supply pipe and a nozzle head engaging over the end of said supply pipe and having an orifice discharging liquid fuel under pressure into said combustion chamber, the combination of a heat shield surrounding said nozzle member for shielding the latter from the radiant heat of the flame during operation of the burner and from the radiant heat of the combustion chamber immediately after stopping the operation of the burner, said heat shield comprising a mounting member and an end head carried thereby, said mounting member being mounted on said nozzle supply pipe at a point substantially in rear of said nozzle head, means for detachably securing said end head to said mounting member, said end 40

head substantially enclosing and shielding said nozzle member from the radiant heat emanating from either of said sources and being supported in spaced relation to said nozzle head to permit a cooling flow of air therebetween, the entire heat shield being supported out of contact with said nozzle supply pipe and nozzle head except at said point of mounting of said mounting member on said nozzle supply pipe in rear of said nozzle head, said end head having an aperture in its front end through which the liquid fuel discharge from the nozzle orifice occurs and through which said cooling flow of air can also discharge, said aperture being of relatively small size whereby the entire conical discharge from the nozzle orifice just clears the edge of the aperture and whereby only a relatively small area of the nozzle head is exposed to radiant heat.

12. In a burner of the class described including a nozzle adapted to discharge liquid fuel under pressure into a combustion chamber, the combination of a thermally insulating shield surrounding said nozzle and operating to shield the nozzle from the radiant heat of the flame during operation of the burner and from the radiant heat of the combustion chamber immediately after stopping the operation of the burner, said shield comprising a cast metal sleeve enveloping said nozzle, and a removable sheet metal end 20 cap mounted on said sleeve, said sleeve and said cap being spaced from said nozzle and being substantially out of heat conducting relation to said nozzle, said end cap having an aperture therein adapted to align with the orifice in said nozzle, the aperture in said cap being relatively small whereby the entire conical discharge of liquid fuel from the nozzle orifice just clears said aperture and whereby the major portion of said nozzle is protected from radiant heat.

WILLIAM F. KLOCKAU.
